CLAIM

The ornamental design for a battery charger for earphones, as shown and described.

DESCRIPTION

FIG. 1 is a front perspective view of a battery charger for earphones showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right-side elevational view thereof;

FIG. 8 is a left-side elevational view thereof;

FIG. 9 is a front perspective view showing the state that the lid is opened thereof;

FIG. 10 is a front elevational view thereof;

FIG. 11 is a rear elevational view thereof;

FIG. 12 is a top plan view thereof;

FIG. 13 is a bottom plan view thereof;

FIG. 14 is a right-side elevational view thereof;

FIG. 15 is a left-side elevational view thereof;

FIG. 16 is a cross-sectional end view taken along line 16-16 in FIG. 3 without internal structure;

FIG. 17 is a cross-sectional end view taken along line 17-17 in FIG. 3 without internal structure;

FIG. 18 is a cross-sectional end view taken along line 18-18 in FIG. 5 without internal structure; and,

FIG. 19 is a front perspective view of the battery charger for earphones, shown in a condition of use.

The broken lines in the drawings depict portions of the battery charger for earphones that form no part of the
